UNITED STATES PATENT OFFICE.

THOMAS D. MONTAGUE, OF MAWRGLEN, PENNSYLVANIA.

IRONING-BOARD.

SPECIFICATION forming part of Letters Patent No. 695,324, dated March 11, 1902.

Application filed May 18, 1901. Serial No. 60,897. (No model.)

To all whom it may concern:

Be it known that I, THOMAS D. MONTAGUE, a citizen of the United States, residing at and whose post-office address is Mawrglen, in the 5 county of Lycoming and State of Pennsylvania, have invented new and useful Improvements in Ironing-Boards, of which the following is a specification.

This invention relates to ironing-boards of 10 that class which are detachable from a wall or like fixed support and are adapted to be folded so as to occupy a minimum amount of space when not in use.

The object of the invention is to provide an 15 ironing-board adapted for ready attachment to the wall of a room or other fixed support, which may be conveniently detached and folded up for storage or transportation, and which will be simple and economical in construction.

My improvement comprises a pair of plates having vertical sockets and adapted to be secured to a wall, a bracket having a horizontal lip and adapted to be secured to the wall 25 above the plates, a board having a supporting-leg, a pair of straps secured to the under side of the board, having pendent pins adapted to engage in the vertical sockets, and a horizontal cam-disk eccentrically pivoted to 30 the board and operating between the latter and the horizontal lip.

In the drawings forming a part of this specification and to which reference is made, Figure 1 is a side or edge view showing my 35 invention adjusted for use. Fig. 2 is a top or plan view of the same. Fig. 3 is an edge view showing the board detached from its fixed support, the leg being folded to form a brace to support the table in an upright 40 position against a wall. Fig. 4 is a perspective of one of the socket-plates, and Fig. 5 is a similar view of one of the straps.

1 is the board, which may be of any approved form and dimensions.

2 is a folding leg suitably hinged or otherwise pivotally connected with the board, and 45 3 are the straps, having pendent pins 3^a and screwed or otherwise secured to the under side of one end of the board. The pins are formed integral with the straps, which are provided with screw-holes, as shown, for ready attachment to the board by means of screws.

4 are plates having pin-sockets 4^a and adapted to be screwed to a wall or other fixed support and adapted to receive the pins of the 55 straps 3 and thereby sustain the board.

5 is a bracket having a horizontal lip 5^a and is in the form of a shouldered plate screwed to a wall in a plane just above that of the surface of the board, and 6 is a cam-disk consisting of an eccentrically-pivoted plate, having a handle 6^a and adapted to engage the bracket and thereby lock and hold the board to the wall or support.

Having described my invention, what I 65 claim as new, and desire to secure by Letters Patent, is—

The combination of a pair of plates having vertical sockets and adapted to be secured to a wall, a bracket having a horizontal lip and 70 adapted to be secured to the wall above the plates, a board having a supporting-leg, a pair of straps secured to the under side of the board having pendent pins, adapted to engage in the vertical sockets, and a horizontal 75 cam-disk eccentrically pivoted to the board and operating between the latter and the horizontal lip.

In testimony whereof I affix my signature in presence of two witnesses.

THOMAS D. MONTAGUE.
